UNITED STATES PATENT OFFICE.

JESSE W. WARRINER, OF SIOUX FALLS, SOUTH DAKOTA.

AUTOMATIC ELECTRIC FAN.

1,238,365.

Specification of Letters Patent. Patented Aug. 28, 1917.

Application filed September 30, 1915. Serial No. 53,355.

To all whom it may concern:

Be it known that I, JESSE W. WARRINER, a citizen of the United States, residing at Sioux Falls, in the county of Minnehaha and State of South Dakota, have invented certain new and useful Improvements in Automatic Electric Fans, of which the following is a specification.

My invention relates to automatic fans, and has for its primary object the provision of a fan of this type which is simple in construction, cheap to manufacture, and strong and durable.

Another object of the invention is to provide a device of the character above mentioned comprising a plurality of independently controllable fans carried by a single frame and driven from a single source of power contained within the frame, the device being particularly adapted for use on dining tables and the like, it being possible for a person to control a fan at the center of the table independently of others who may be seated at the same table.

With the above and other objects in view my invention resides preferably in the construction, combination, and arrangement of parts as hereinafter set forth in the specification as illustrated in the accompanying drawings, in which—

Figure 1 is a side elevation of the fan embodying the improvements of my invention;

Fig. 2 is a top plan view of the same;

Fig. 3 is a similar view showing the cover removed, and

Fig. 4 is a vertical sectional view taken on the line 4—4 of Fig. 3 looking in the direction of the arrow.

Similar reference characters designate similar parts throughout the various views of the drawings.

In the drawings, I have illustrated a fan embodying the improvements of my invention comprising a base 1 from which a hollow standard or column 2 extends, said column terminating at its upper extremity in a semi-elliptical housing 3, said housing being closed by a suitable cover 4 forming a substantially elliptical body, suitable fastening means such as screws 5 being provided.

The standard 2 is extended in the bottom of the housing 3 as indicated at 6 and serves to support rigidly an electric motor or the like 7. An annular flange 8 is provided on the portion 6 of the standard 2 and a disk 9 is freely rotatable on said portion 6 above

said flange, said disk being provided with bevel gear teeth 10.

The armature shaft of the motor 7 is extended as indicated at 11 and carries a pinion 12 for engagement with the gear teeth 10. Thus when the motor runs the gear 9 will be caused to rotate.

A plurality of fans substantially identical in construction are provided, each fan being in operative engagement with the gear teeth 10 in the manner hereinafter described and in view of the fact that these fans are identical, I will describe but one of them. A plurality of shafts 13 are arranged radially of the center of said housing 3, said shafts being mounted in brackets 14 carried by the motor casing and in suitable bearing openings 15 provided in the bottom 3 of a housing. On the outer extremities of said shafts, fans 16 are mounted. Pinions 17 are freely rotatable on shafts 13, clutches 18 being provided for causing engagement of said pinions with their respective shafts. The clutches 18 are slidable on the respective shafts 13 and coact with clutch faces on the pinions 17 as shown in Fig. 3. Suitable levers 19, links 20 and operating handles 21 may be provided for moving said clutches to engage the pinions with their respective shafts. It will be noted that operating handles 21 are disposed in a convenient position so that persons desiring to operate the fans need not endanger their hands from contact with the mechanism close to the fan. Suitable guards 22 may be provided over each of the fans, these guards being of the usual construction.

Attention is called to the fact that the outside appearance of the device is pleasing to the eye, none of the operating mechanism being visible, which not alone makes the device novel, but also reduces the liability of danger, owing to the possibility of accident. The electric conductors are designated 23 and may enter through the base of the device as shown in Figs. 1 and 4.

From the above description taken in connection with the accompanying drawings, it is thought that a clear and comprehensive understanding of the construction, operation and advantages of my invention may be readily gathered and while I have shown and described the same as embodying a specific structure, I reserve the right to make changes therein which do not depart

from the spirit and scope of the invention as claimed.

What is claimed is:

- 5 1. An automatic fan, comprising a base, a housing on said base, a motor in said housing, said motor having engagement with a gear, and a plurality of fans independently controllable adapted for engagement with said gear.
- 10 2. An automatic fan, including a base, a vertical standard on said base, a housing on said standard, a motor in said housing, a plurality of fans having shafts and pinions, a gear rotatable by the motor and being in engagement with the pinions, and means for disconnecting the fan shaft from the respective pinion.
- 15 3. An automatic fan, including a base, a standard on said base, a housing carried by said standard, a motor in said housing, a toothed disk rotatable about said motor and having operable engagement therewith, a plurality of fans, and means for independently controlling said fans.
- 20 4. An automatic fan, including a base, a standard on said base, a housing carried by the standard, a motor in said housing, a

relatively large gear having operative engagement with said motor, a plurality of fans mounted on radially arranged shafts, 30 pinions on said shafts, clutches for independently controlling said shafts whereby to engage and disengage said fans from their respective pinions.

5. An automatic fan, including a base 35 having a standard extending therefrom, a housing carried by said standard, a motor in said housing, a relatively large gear concentrically mounted in said housing, a bearing for said gear formed on said standard, 40 said gear having operative connection with said motor, a plurality of fan shafts radially disposed in said housing, pinions carried by said shafts, clutches for each of said shafts, and fans mounted on the outer 45 extremities of said shafts, as and for the purpose set forth.

In testimony whereof I affix my signature in presence of two witnesses.

JESSE W. WARRINER.
